United States Patent

Des. 238,706

Patented Feb. 3, 1976

238,706

ELECTRONIC FLASH UNIT

Jochen Kramer, Wolfsburg, and Claus Prochnow,
Braunschweig, Germany, assignors to Rollei-Werke
Franke & Heidecke, Braunschweig, Germany

Filed Aug. 27, 1974, Ser. No. 501,099

Claims priority, application Germany Mar. 4, 1974

Term of patent 14 years

Int. Cl. D16—05

U.S. Cl. D61—1 F

FIG. 1

FIG. 4

FIG. 2

FIG. 5

FIG. 3

FIG. 6

FIG. 1 is a top plan view of an electronic flash unit, showing our new design;

FIG. 2 is a front elevational view thereof;

FIG. 3 is a rear elevational view thereof;

FIG. 4 is a left side view thereof;

FIG. 5 is a right side view thereof; and

FIG. 6 is a bottom plan view thereof.

We claim:

The ornamental design for an electronic flash unit, substantially as shown.
